US0D1111268S

(12) **United States Design Patent** (10) **Patent No.:** **US D1,111,268 S**
(45) **Date of Patent:** **** Feb. 3, 2026**

(54) **WASHING MACHINE**

- (71) Applicant: **Samsung Electronics Co., Ltd.**, Suwon-si (KR)
- (72) Inventors: **Seungwook Suh**, Suwon-si (KR); **Jichang Kang**, Suwon-si (KR); **Euikyun Koh**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/970,808**
- (22) Filed: **Oct. 30, 2024**

(30) **Foreign Application Priority Data**

- Aug. 20, 2024 (KR) 30-2024-0033307
- (51) LOC (15) Cl. **15-05**
- (52) U.S. Cl. USPC **D32/6**

(57) **CLAIM**

The ornamental design for a washing machine, as shown and described.

DESCRIPTION

FIG. 1 is a front right perspective view of a washing machine, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the encircled portion 8 in FIG. 1;

FIG. 9 is an enlarged view of the encircled portion 9 in FIG. 1; and,

FIG. 10 is an enlarged view of the encircled portion 10 in FIG. 1.

The even-dash broken lines illustrating portions of the washing machine form no part of the claimed design. The dot-dash lines encircling enlargement portions of the washing machine form no part of the claimed design.

1 Claim, 10 Drawing Sheets
